UNITED STATES PATENT OFFICE.

CHRISTOPHER WEBSTER, OF PROVIDENCE, RHODE ISLAND, ASSIGNOR TO THE GORHAM MANUFACTURING COMPANY, OF SAME PLACE.

TOP FOR FLASKS OR SIMILAR ARTICLES.

SPECIFICATION forming part of Letters Patent No. 613,850, dated November 8, 1898.

Application filed July 23, 1897. Serial No. 645,727. (No model.)

To all whom it may concern:

Be it known that I, CHRISTOPHER WEBSTER, of Providence, in the county of Providence and State of Rhode Island, have invented a new and useful Improvement in Tops for Flasks or Similar Articles; and I hereby declare that the following is a full, clear, and exact description of the same, reference being had to the accompanying drawings, forming part of this specification.

This invention has reference to an improvement in the ornamental tops used on flasks; and it consists in the peculiar construction of and in the combination of the parts, as will be more fully set forth hereinafter.

The object of the invention is to provide a top for a flask or bottle by the use of which the flask may be tightly closed without danger of leaking and which when desired may be locked, so that it cannot be opened by unauthorized persons.

Figure 1 is a side view of top, and Fig. 2 a vertical sectional view of the same. Fig. 3 is a sectional view of the parts below the hinged cover, showing the latch in side view. Fig. 4 is a plan view of the graduated ring as seen from below. Fig. 5 is a plan view of the lower locking-ring.

In the drawings, A indicates the cylindrical tube, provided with the enlarged socket a, by which it is secured to the flask, bottle, or other receptacle. Its open end extends above the hinge by which the top is secured and forms a projecting outlet from which liquid can be poured more conveniently than when the outlet is at the hinged joint.

B is an annular ring provided with the stud b and the notch b'. The ring B is loose on the tube A.

C is an annular ring provided with the vertical slot c'. This annular ring C is secured to the socket a by solder. Resting on the annular ring C is the annular ring D, having the beaded rim d, projecting beyond the ring C, the annular shoulder d', fitting loosely the inside of the ring C, and the shoulder d'', which extends inside of the stud b to the ring B. The shoulder d' has the recess d'', and the annular surface of the ring has the projecting stud d'.

E is the annular hinge-ring. It has the eye e, to which the latch F is pivotally se-

cured, and the hinge e', to which the annular ring supporting the cover is secured.

The cover consists of the head H, made in the form of a knob or any other desired form, the cylindrical neck I, the annular flange K above the hinged ring G, the annular flange L below the hinged ring G, and the cylindrical cams M on the inner side of the cylindrical neck. The upper end of the cylinder A has the conical cam-piece N secured to it. The interior of the head H is filled with any suitable material, and its lower surface is faced with an elastic packing-disk, preferably of cork.

In closing or opening the head H is turned in the hinged ring G to bring one of the cams M under the cam N or turn the cam away from the same. By turning the head to bring the cam M under the cam N sufficient strain is exerted to bring the outlet end of the cylindrical base A tightly against the disk N, and therefore an absolutely tight joint is secured.

When it is desired to lock the top, so as to prevent the unauthorized opening of the receptacle, the annular ring D is turned until the stud d' engages with the stud b and turns the annular ring B to bring the notch b' opposite the vertical slot c' in the fixed ring C. The annular ring D is now turned back until the notch d'' is also opposite the vertical slot in the ring C. The end F' of the latch F is now pushed into the two notches d'' and b'. The annular ring D is turned until the stud d' engages with the stud b and turns the annular ring sufficiently to bring the peripheral surface of both the rings B and D against the face of the end F' of the latch F and the hook F² over the annular flange K. The head H may now be turned around to release the pressure of the cams, but the hook F² of the latch F holds the head from being opened.

As the notches b' and d'' cannot be seen a mark is placed on the beaded edge d of the annular ring D, known to the owner or one initiated, and the annular ring C is graduated and marked, so that by turning the ring D until the mark is opposite the mark on the ring C the notch b' will be opposite the vertical slot c' and the end F' of the latch. By now turning the ring D so that the mark is opposite another mark of the graduation on the

ring C the notch d^3 will also be opposite the vertical slot c' in the ring C, and the lower end F' of the latch F can be pushed to swing the hook F² away from the flange K and allow 5 the head to swing back on the hinge, so that the contents may be poured out.

By changing the positions of the studs b' and d^4 on the respective annular rings D and B a great variety of combinations can be 10 made, so that each top will materially differ from every other and, unless the combination of each is known, cannot be opened.

Having thus described my invention, I 15 claim as new and desire to secure by Letters Patent—

In a top for a flask or similar article, the combination with a tube adapted to be secured to a flask, a hinge-ring secured midway the vertical length of the tube, a head pro-

vided with an elastic disk and having a neck 20 surrounding the upper end of the tube and rotatably secured in a hinged ring, and cams secured to the upper end of the tube and the inside of the neck, of the annular ring D having the notch d^3 and stud d^4 , the annular ring B having the notch b' and the stud b , the graduated ring C having the slot c' and the latch F; whereby the outlet is sealed by the rotation of the head and the head locked by the rotation of the annular ring D, substantially in the manner and for the purpose described.

In witness whereof I have hereunto set my hand.

CHRISTOPHER WEBSTER.
